UNITED STATES PATENT OFFICE

EDWIN O. KLEMM, OF SAGINAW, MICHIGAN

DESIGN FOR A SETTEE WITH READING AND WRITING ATTACHMENTS

Application filed January 20, 1931. Serial No. 38,397. Term of patent 14 years.

To all whom it may concern:

Be it known that I, EDWIN O. KLEMM, a citizen of the United States, residing at Saginaw, in the county of Saginaw and State of Michigan, have invented a new, original and ornamental Design for Settee with Reading and Writing Attachments, of which the following is a specification, reference being had to the accompanying drawing, forming a part thereof, in which the figure is a perspective view of a settee with reading and writing attachments, showing my new design.

I claim—

The ornamental design for a settee with reading and writing attachments, substantially as shown.

EDWIN O. KLEMM.
